UNITED STATES PATENT OFFICE

JOHN V. PALMER, OF PITTSBURGH, PENNSYLVANIA, ASSIGNOR OF ONE-THIRD TO HARRY I. NEAMAN AND ONE-THIRD TO JAMES M. MAGEE, BOTH OF PITTSBURGH, PENNSYLVANIA

CONNECTER FOR RAILWAY RAILS

Application filed January 9, 1932. Serial No. 585,702.

The general object which I have in view is the provision of a new form of rail-connecter which will provide the proper connection between and support for the ends of alined rails, 5 which will be inexpensive to manufacture and which may be readily and conveniently installed and removed.

For these purposes I have provided a rail-connecter which comprises fish plates bridging the joint and fitting adjacent the opposite sides of the rail web; clamping plates also bridging the joint and fitting against the fish plates, the rails, fish plates and clamping plates being tightly bolted together by bolts 15 extending through registering holes in the elements. The fish plates and clamping plates preferably support the rail head from beneath. The skirts of the fish plates are bent first outwardly, to bear on the bases of 20 the rails, and then downwardly to protrude below said bases, and said skirts are provided with horizontally elongated openings or slots to receive the end tongues of the chair which is located beneath the rail ends at the joint 25 and to support the rail ends from beneath.

The chair is provided with abutment portions which bear against the clamping plates from within and thus prevent relative movement between the chair and the other elements of the connecter when the nuts are 30 tightened up on the bolts.

The tongues of the chair are provided with openings through which members may be driven wedging against the outer faces of the 35 clamping plates.

In case the joint is superimposed on a tie, these members, which may be rail spikes, may be driven down into the tie.

Where the joint is superimposed on a tie, 40 a filler plate is introduced between the chair and the tie to support the chair from below.

Other novel features of construction, and also of arrangement of parts, will appear from the following description.

45 In the accompanying drawing, wherein I have illustrated a practical embodiment of the principles of my invention, Fig. 1 is a perspective view showing two rail ends provided with my improved connecter.

50 Fig. 2 is a cross sectional view taken in

a transverse plane at the joint, a tie, not shown in Fig. 1, being illustrated as located beneath the joint.

Fig. 3 is a perspective view of one of the fish plates.

Fig. 4 is a like view of one of the chairs.

Fig. 5 is a like view of a clamping plate.

Fig. 6 is a like view of the filler plate.

Referring to the drawing, 1 represents the abutting ends of two alined rails which are supported by the cross ties 2. In Fig. 2 I show a third tie, 2a, located underneath the joint.

In the drawing I have illustrated the rails as of the T-type, such as are in standard steam-railway use, but it will be understood that my invention is equally applicable to rails of the girder or other types also in use.

3 represents the fish plate, one of which fits up against each side of the webs of the rails, bridging the joint, and preferably fits between the head of the rails and their bases to brace the rail ends against flexing.

4 represents the two clamping plates which fit against the outer faces of the fish plates also bridging the joint.

The top edges of the clamping plates preferably fit under the outturned top flanges 3a of the fish plates, thus also supporting the rail heads. The skirts of the clamping plates are bent to bear on the rail bases as at 5 and to extend down below said bases as at 6.

The rail ends, the fish plates and the clamping plates are all clamped tightly together by the bolts 7 which extend through registering holes in the elements, and upon which the nuts 8 are screwed tightly. The clamping plates are preferably of less length than the fish plates and are engaged only by the two center bolts.

Below the bases of the rails the portions 6 of the clamping plates 4 are provided with the horizontally elongated openings or slots 9 to receive the end tongues 10 of the rail chair 11, said tongues being of proper dimensions to suitably fit the slots 9. The chair is provided with suitable abutments or shoulders 12 which bear outwardly against the clamping plates 4 and thus prevent rela-

tive movement of the chair. The chair overlaps the joint from below and thus supports the rail ends against flexing.

13 represents holes in the tongues 10 at 5 the outer side of the chair, and 14 represents dowel members or wedges, which are preferably railway spikes which are driven into said holes and thus wedged against the clamping plates.

10 Where, as in Fig. 2, a tie, 2a, is located under the rail joint, a filler plate 15 is interposed between the tie and the chair to furnish the latter undersupport, and said plate has upturned flanges 16 at its ends to engage the 15 sides of the chair and thus prevent relative movement between the filler plate and the chair. In such case the spikes 14 are driven down into the tie 2a.

It is obvious from the foregoing that my 20 improved rail joint is simple in construction and provides firm and efficient connection and support for the rail ends. It is readily installed and removed.

One of the advantageous features of my 25 improved connector is that its elements may be conveniently rolled and thus its cost of manufacture is kept low.

I claim:—

1. A connector for rail ends, comprising 30 a pair of fish plates bridging the rail joint and fitting adjacent the webs of the rails, a pair of clamping plates also bridging the joint and bearing inwardly against the fish plates, bolts extending through registering 35 holes in the rails, fish plates and clamping plates to clamp the elements together, the clamping plates having skirts depending below the rails and said skirts being provided with openings, and a chair supporting the 40 rail ends from below and having tongues engaging said openings and abutments bearing outwardly against the clamping plates.

2. A connector for rail ends, comprising 45 a pair of fish plates bridging the rail joint and fitting adjacent the webs of the rails, a pair of clamping plates also bridging the joint and bearing inwardly against the fish plates, bolts extending through registering 50 holes in the rails, fish plates and clamping plates to clamp the elements together, the clamping plates having skirts depending below the rails and said skirts being provided with openings, a chair supporting the rail 55 ends from below and having tongues engaging said openings and abutments bearing outwardly against the clamping plates, and said tongues having holes therein and wedge members driven into said holes and bearing inwardly against said clamping plates.

60 3. A connector for rail ends, comprising a pair of fish plates bridging the rail joint and fitting adjacent the webs of the rails, said fish plates having their longitudinal edges bearing against the base and the head 65 of the rails and being provided with out-

wardly extending flanges along their upper longitudinal edges, a pair of clamping plates also bridging the joint and bearing inwardly against the fish plates, the tops of said clamping plates bearing upwardly against 70 said flanges and their bottoms bearing against the rail bases, bolts extending through registering holes in the rails, fish plates and clamping plates to clamp the elements together, said clamping plates having 75 skirts depending below the rail bases and said skirts being provided with openings, and a chair supporting the rail ends from below and having tongues engaging said openings and abutments bearing outwardly 80 against the clamping plates.

4. A connector for rail ends, comprising a pair of fish plates bridging the rail joint and fitting adjacent the webs of the rails, said fish plates having their longitudinal edges bearing against the base and the head of the rails and being provided with outwardly extending flanges along their upper longitudinal edges, a pair of clamping plates also 90 bridging the joint and bearing inwardly against the fish plates, the tops of said clamping plates bearing upwardly against said flanges and their bottoms bearing against the rail bases, bolts extending through registering holes in the rails, fish 95 plates and clamping plates to clamp the elements together, said clamping plates having skirts depending below the rail bases and said skirts being provided with openings, a chair supporting the rail ends from below 100 and having tongues engaging said openings and abutments bearing outwardly against the clamping plates, and said tongues having holes therein and wedge members driven into said holes and bearing inwardly against said 105 clamping plates.

5. A connector for rail ends where a cross tie is disposed beneath the rail joint, comprising a pair of fish plates bridging the rail joint and fitting adjacent the webs of the 110 rails, a pair of clamping plates also bridging the joint and bearing inwardly against the fish plates, bolts extending through registering holes in the rails, fish plates and clamping plates to clamp the elements together, the 115 clamping plates having skirts depending below the rails and said skirts being provided with openings, a chair supporting the rail ends from below and having tongues engaging said openings and abutments bearing outwardly 120 against the clamping plates, said tongues being provided with holes, and fastening members driven through said holes into the tie.

6. A connector for rail ends where a cross tie is disposed beneath the rail joint, comprising a pair of fish plates bridging the rail joint and fitting adjacent the webs of the rails, a pair of clamping plates also bridging the joint and bearing inwardly against the 130

fish plates, bolts extending through registering holes in the rails, fish plates and clamping plates to clamp the elements together, the clamping plates having skirts depending 5 below the rails and said skirts being provided with openings, a chair supporting the rail ends from below and having tongues engaging said openings and abutments bearing outwardly against the clamping plates, said 10 tongues being provided with holes, fastening members driven through said holes into the tie, and a filler plate interposed between the tie and the chair.

7. A connector for rail ends where a cross tie is disposed beneath the rail joint, comprising a pair of fish plates bridging the rail joint and fitting adjacent the webs of the rails, a pair of clamping plates also bridging the joint and bearing inwardly against the 20 fish plates, bolts extending through registering holes in the rails, fish plates and clamping plates to clamp the elements together, the clamping plates having skirts depending below the rails and said skirts being provided 25 with openings, a chair supporting the rail ends from below and having tongues engaging said openings and abutments bearing outwardly against the clamping plates, said tongues being provided with holes, fastening 30 members driven through said holes into the tie, and a filler plate interposed between the tie and the chair, said filler plate having a portion engaging the chair to prevent relative movement.

35 Signed at Pittsburgh, Pa., this 30th day of December, 1931.

JOHN V. PALMER.
